MACHINE FOR FORMING CRANKS

Application filed June 30, 1927, Serial No. 202,535, and in Germany July 15, 1926.

My present invention relates to machines for bending rod-like blanks, and particularly for forming cranks on shafts. The type of machine which I seek to improve by my present invention comprises two clamps or holders adapted to grasp the rod or stock at each side of the portion in which the bend is to be formed, said clamps being combined with mechanism for varying the distance between them, said clamps being coaxial and the distance between them being reduced gradually during the formation of the bend or crank. The portion of the work or blank between said clamps or holders is engaged by a member movable transversely of the blank axis. In prior constructions of this type, provision has been made for moving said intermediate member transversely during the entire time that the distance between the other two members or clamps was being reduced, and this result was obtained either by an operative connection between the two mechanisms effecting longitudinal and transverse movement respectively, or by means of independent mechanisms. I have found that materially improved results are obtained by employing the mechanism which moves the intermediate member; only for starting the transverse movement of said member, the further transverse movement of this member not being produced by any mechanism acting thereon directly, but resulting simply from the bending of the intermediate blank portion due to the relative longitudinal movement of the clamps or holders at each side of such portion. Other features of my invention will be pointed out hereinafter.

Without desiring to restrict myself to the specific details illustrated, I will now describe a preferred and satisfactory embodiment of my invention, with reference to the accompanying drawings, in which Fig. 1 is a front elevation of a crank-forming machine of my improved type; Fig. 2 is an end elevation thereof, looking from the left of Fig. 1; Fig. 3 is a front elevation of the parts shown at the central upper portion of Fig. 1, with a blank in position; and Fig. 4 is a detail end elevation of the in-

termediate member which gives the initial bend to the crank.

The machine illustrated comprises a base 1 with standards 2, 3 rising at the ends thereof and carrying horizontal guide or track members 4, 5 respectively on which the upsetting slides, clamps, or holders 6, 7 respectively are adapted to move in line with each other. These slides may be of any suitable construction, being provided, for instance, with hinged covers 8, 9 respectively to enable upsetting dies to be inserted and removed, the dies and the blank or stock therein, being held in place in such clamps or holders by levers 10, 11 pivoted to said holders or slides and having cam surfaces to engage corresponding faces on the covers 8, 9. To each of the upsetting slides 6, 7 is secured rigidly a pair of longitudinal rods 12 or 13 respectively, provided with notches co-operating with pawls 14 to hold in position, longitudinally-adjustable abutments 15 adapted to engage the ends of the blank, rod, or shaft held in the dies of the clamps or slides 6, 7. To provide for a finer adjustment than the pawls 14 and the notches will permit, the members 15 may carry screws 16 adjustable lengthwise, the inner ends of said screws constituting the abutments proper which engage the ends of the blank.

The mechanism for moving the slides 6, 7 toward each other during the operation, and from each other after the completed crank shaft has been removed, consists of transverse bolts or pivots 17, 18 respectively, each connected with the upper ends of a pair of rocker arms 19, 20 respectively. The lower ends of these rocker arms are connected pivotally with arms 21, 22 respectively fulcrumed at 23, 24 respectively on stationary brackets 25, 26 respectively. At the upper portions of the rocker arms are provided pivot bolts 27, 28 for connection with the upper or outer ends of rods 29, 30 respectively, preferably of the longitudinal-extensible type; for instance, each of said rods may consist of oppositely threaded sections connected by a nut or turnbuckle 31, 32 respectively. The other ends of the con-

necting rods 29, 30 are pivotally connected with crank pins 33, 34 respectively on toothed wheels 35, 36 respectively. There are two wheels 35 and two wheels 36, held to rotate with shafts 37, 38 respectively journalized in bearings 39 on the standards 2 and 3. The wheels 35, 36 are shown as spur wheels meshing with spur pinions 40, 41 respectively, rigidly mounted on shafts 43, 44 journalized in bearings 42 likewise carried by the standards 2, 3. The shafts 43, 44 also carry at their central portions, worm wheels 45, 46 respectively in mesh with worms 47, 48 respectively mounted on a shaft 49, journalized in stationary bearings, between the standards 2, 3, and extending parallel to the path of the slides 6, 7. This shaft may be driven by means of a belt pulley 51 mounted thereon loosely, and adapted to be connected therewith in any suitable manner, as by a friction clutch 50. To control the clutch, I may provide a pedal 52, the rock shaft 53 of which is journalized in stationary bearings 54, and has a crank arm 55 having a pin-and-slot connection with one end of a lever 56 swinging in a plane at right angles to the plane of motion of the crank arm 55. The other end of the two-armed lever 56 is connected pivotally with a rod 57, having a like connection with one end of the two-armed clutch-shifting lever 58, forked to embrace the grooved clutch collar, and fulcrumed at 59 on a stationary bracket.

Between the two standards 2, 3 there is provided a suitable stationary guide 61' in which is movable vertically a slide 61 constituting an intermediate member located half-way between the clamps or slides 6, 7. At its upper end, the slide 61 is provided with a seat 62 for the reception of sleeves or bushings (not shown) employed to embrace the central portion of the shaft and to bend it downwardly. To said upper end is hinged a cover 63, recessed at its lower surface to conform to the seat 62, and normally locked in position by a suitable device, such as an arm 64 pivoted to the upper end of the slide 61 and carrying pivotally a cam lever 65 adapted to co-operate with a corresponding formation on the upper surface of the cover 63. The slide 61 is provided with rack teeth 60 in mesh with a spur pinion 66, rigidly connected with a spur wheel 67 mounted on a shaft 68 journalized in the standards 2, 3. The spur wheel 67 meshes with a pinion 69 mounted rigidly on a shaft 70. At one end of this shaft, exteriorly of the standards 3, is mounted loosely a handwheel 71, the hub of which is provided with clutch teeth adapted to engage companion clutch teeth on a clutch collar 72 rigidly secured to the shaft 70. The clutch teeth are normally held out of engagement by means of a spring 71' tending

to move the handwheel 71 away from the clutch collar 72.

The operation is as follows: By means of the handwheel 71, the intermediate member or slide 61 is first moved upwardly until the opening formed by the seat 62 and cover 63 is in axial alignment with the blank-receiving portions of the clamps or slides 6, 7, the latter having been adjusted to the proper distance from each other (according to the work to be performed), by means of the turnbuckles 31, 32, or by changing the points at which the actuating rods 29, 30 are connected with the rocker arms 19, 20. For instance, as shown in Fig. 1, said arms may be provided with a plurality of holes to receive the pivotal connections with the rods 29, 30, said holes being at different distances from the lower ends of the rocker arms. Fig. 1 shows the rods 29, 30 connected with the upper set of holes, the lower set of holes being indicated at 19', 20'. This adjustment of the points of connection of the arms 19, 20 with the rods 29, 30 respectively, in conjunction with the turnbuckle 70 adjustment, also enables me to vary the stroke of the slides 6, 7 within relatively wide limits, so that the machine is adapted for making cranks of different lengths. The shaft or other blank, having been heated to the proper temperature, is placed in the axially-aligning dies or sockets of the slides or clamps 6, 7 and of the intermediate member 61, 63, and is securely held in place by operating the levers 10, 11, and 65. The handwheel 71 is then engaged with the clutch collar 72 and rotated in the proper direction to pull the slide 61 downwardly, transversely to the axis of the blank or shaft. This gives the shaft an initial bend at the portion where the crank is to be produced. The operator then depresses the pedal 52 to throw in the clutch 50 and start the rotation of shafts 37, 38. By means of the actuating rods 29, 30, the rotation of said shafts causes the slides 6, 7 to move uniformly toward each other and toward the intermediate member 61, 63, so that the latter will always be at equal distances from the slides or clamps 6, 7. As soon as these slides begin to move, the operator releases the handwheel 71, and the spring 71' will disengage said wheel from the clutch collar 72. When the handwheel is released, the slide 61 will no longer be moved downward positively, by force applied to turn said wheel, but will move in its guide 61' in response to the deflection imparted to the crank portion of the shaft by the pressure of the slides 6, 7 moving toward each other.

In order to limit the downward movement of the slide 61, and thereby determine the length of the crank formed on the shaft, the frame of the machine is provided with an opening 73 beneath the path of said slide,

and through this opening may be inserted plates of different thickness, or a different number of plates, to constitute, in effect, an adjustable stop or abutment for arresting the downward or outward movement of the slide 61 at the proper point to give the desired length to the crank formed on the shaft. As soon as the slide 61 is thus arrested, the further inward movement of the 10 clamps or slides 6, 7 will upset the shaft portion between them. The crank is formed with a full cross-section, since the material can not yield or flex in any direction except as intended. The sides or flanks of the 15 crank are formed between the longitudinally-moving upsetting slides 6, 7 and the intermediate transversely-moving member 61, 63. The latter is made very thin, so that the pin of the crank may be given different 20 lengths by inserting sleeves or bushings of different lengths between the cover 63 and the upper portion or seat 62 of the slide 61.

The intermediate member 61, 62, 63, 64, 25 65 may be removed readily from the machine (by pulling such member out upwardly), and in this condition the machine may be used for ordinary upsetting operations, say to form collars on a shaft or rod, either at the end or at an intermediate portion.

30 Various modifications may be made without departing from the nature of my invention as set forth in the appended claims.

I claim as my invention:

1. A machine of the class described, comprising aligning holders for a blank which are movable toward and from each other, an intermediate member arranged to engage the blank between said holders, actuating mechanism temporarily operative for starting said intermediate member in a direction transverse to the path of said holders to impart an initial bend to the intermediate portion of said blank, said holders being stationary relatively to each other during the starting operation of said intermediate member, mechanism operative subsequently to the operation of said actuating mechanism for moving said holders toward each other whereby the intermediate portion of said blank is forced farther in said transverse direction to complete the bend therein, said intermediate member continuing to move in its transverse path in response to the deflection imparted to said intermediate portion of the blank by the pressure of the holders moving toward each other, and a guide for maintaining the intermediate member in its transverse path of movement.

60 2. A machine of the class described, comprising axially-aligning blank holders movable relatively to each other lengthwise of their axis, an intermediate member arranged to engage the blank between said holders, actuating mechanism temporarily operative

for starting said intermediate member in a direction transverse to said axis, to give the blank an initial lateral bend, said holders being stationary relatively to each other during the starting operation of said intermediate member, mechanism operative subsequently to the operation of said actuating mechanism for reducing the distance between said holders whereby said blank, at said initial bend, is forced farther laterally to complete the bend therein, said intermediate member continuing to move in its transverse path in response to the deflection imparted to said blank at said bend by the pressure of the holders moving toward each other, and a guide for confining said member to movement in said direction as the reduction of the distance between the holders causes a further lateral bending of the intermediate portion of the blank.

3. A machine according to claim 2, provided with a regulatable stop to determine the outward stroke of the intermediate member.

4. A machine according to claim 1, in which the mechanism for moving the aligning holders comprises rocker arms connected with said holders, crank mechanisms with extensible connecting rods for operating said rocker arms, and a drive shaft common to both crank mechanisms.

5. A machine according to claim 1, in which the mechanism for moving the aligning holders comprises rocker arms connected with said holders, connecting rods for actuating said rocker arms, and a drive shaft having crank mechanisms for operating said connecting rods.

6. A machine according to claim 1, in which the mechanism for moving the aligning holders comprises rocker arms connected with said holders, connecting rods attachable to said rocker arms at points located at different distances from the axes of the rocking movement, and a drive shaft having connections for actuating said rods.

7. A machine according to claim 1, in which the mechanism for moving the aligning holders comprises rocker arms connected with said holders, and provided with pivot-receiving formations at different distances from the axes of the rocking movement of said arms, connecting rods attachable to said rocker arms at said pivot-receiving formations, and actuating mechanism for said rods.

8. A machine according to claim 1, in which the mechanism for moving the aligning holders comprises rocker arms connected with said holders, extensible connecting rods attachable to said rocker arms at different distances from the axes of the rocking movement, and actuating mechanism for said rods.

9. A machine according to claim 2, in

which the intermediate member is formed with a rack and co-operates with starting mechanism adapted to be operated manually.

10. A machine of the class described, comprising aligning blank holders movable relatively to each other to increase or diminish the distance between them, an intermediate member arranged to engage the blank between said holders, actuating mechanism temporarily operative for moving said intermediate member in a direction transverse to that in which the relative movement of the said holders takes place, to give the blank an initial lateral bend, said holders being stationary relatively to each other during the formation of said initial bend, mechanism operative subsequently to the operation of said actuating mechanism for reducing the distance between said holders whereby said blank, at said initial bend, is forced farther laterally to complete the bend therein, said intermediate member continuing to move in its transverse path in response to the deflection imparted to said blank at said bend by the pressure of the holders moving toward each other and a regulatable stop to determine the outward stroke of said intermediate member.

11. A machine of the class described, comprising aligning blank holders movable toward and from each other, an intermediate member arranged to engage the blank between said holders, actuating mechanism, temporarily operative, for moving said intermediate member in a direction transverse to that in which the movement of said holders takes place for imparting an initial bend to the blank, and an actuating device operative subsequently to the operation of said actuating mechanism for moving said aligning holders toward each other whereby said blank, at said initial bend, is forced farther laterally to complete said bend, said intermediate member continuing its transverse movement in response to the continued deflection of said blank at said bend, said actuating device comprising rocker arms connected with said holders, crank mechanisms with extensible connecting rods for operating said rocker arms, and a drive shaft common to both crank mechanisms.

12. A machine of the class described, comprising aligning blank holders movable toward and from each other, an intermediate member arranged to engage the blank between said holders, actuating mechanism, temporarily operative, for moving said intermediate member in a direction transverse to that in which the movement of said holders takes place for imparting an initial bend to the blank, and an actuating device operative subsequently to the operation of said actuating mechanism for moving said aligning holders toward each other whereby said blank, at said initial bend, is forced

farther laterally to complete said bend, said intermediate member continuing its transverse movement in response to the continued deflection of said blank at said bend, said actuating device comprising rocker arms connected with said holders, connecting rods for actuating said rocker arms, and a drive shaft having crank mechanisms for operating said connecting rods.

13. A machine of the class described, comprising aligning blank holders movable toward and from each other, an intermediate member arranged to engage the blank between said holders, actuating mechanism, temporarily operative, for moving said intermediate member in a direction transverse to that in which the movement of said holders takes place for imparting an initial bend to the blank, and an actuating device operative subsequently to the operation of said actuating mechanism for moving said aligning holders toward each other whereby said blank, at said initial bend, is forced farther laterally to complete said bend, said intermediate member continuing its transverse movement in response to the continued deflection of said blank at said bend, said actuating device comprising rocker arms connected with said holders, connecting rods attachable to said rocker arms at points located at different distances from the axes of the rocking movement, and a drive shaft having connections for operating said rods.

14. A machine of the class described, comprising aligning blank holders movable toward and from each other, an intermediate member arranged to engage the blank between said holders actuating mechanism, temporarily operative, for moving said intermediate member in a direction transverse to that in which the movement of said holders takes place for imparting an initial bend to the blank, and an actuating device operative subsequently to the operation of said actuating mechanism for moving said aligning holders toward each other whereby said blank, at said initial bend, is forced farther laterally to complete said bend, said intermediate member continuing its transverse movement in response to the continued deflection of said blank at said bend, said actuating device comprising rocker arms connected with said holders and provided with pivot-receiving formations at different distances from the axes of the rocking movement of said arms, connecting rods attachable to said rocker arms at said pivot-receiving formations, and operating mechanism for said rods.

15. A machine of the class described, comprising aligning blank holders movable toward and from each other, and intermediate member arranged to engage the blank between said holders actuating mechanism,

- temporarily operative, for moving said intermediate member in a direction transverse to that in which the movement of said holders takes place for imparting an initial bend to the blank, and an actuating device operative subsequently to the operation of said actuating mechanism for moving said aligning holders toward each other whereby said blank, at said initial bend, is forced farther laterally to complete said bend, said intermediate member continuing its transverse movement in response to the continued deflection of said blank at said bend, said actuating device comprising rocker arms connected with said holders, extensible connecting rods attachable to said rocker arms at different distances from the axes of the rocking movement, and operating mechanism for said rods.
16. A machine of the class described, comprising aligning blank holders movable relatively to each other to increase or diminish the distance between them, an intermediate member arranged to engage the blank between said holders, and formed with a rack, a starting mechanism, adapted to be temporarily operated manually, cooperating with said rack to start said intermediate member in a direction transverse to that in which the relative movement of said holders takes place for imparting an initial bend to said blank, and mechanism operative subsequently to the operation of said starting mechanism for reducing the distance between said holders whereby said blank, at said initial bend, is forced farther laterally to complete the bend therein, said intermediate member continuing its transverse movement in response to the continued deflection of said blank at said bend.

17. The process of forming lateral bends in rodlike blanks, which consists in giving an initial lateral bend to the blank while holding two of its portions in axial alignment and stationary at a constant distance from each other at each side of such bend, and thereupon completing such lateral bend by reducing the distance between said axially-aligning portions and permitting the bent intermediate portion of the blank to move outwardly to completion in response to the pressure exerted by the approach of said axially-aligning portions to each other.

In testimony whereof, I have signed this specification.

KARL AUERBACH.
